UNITED STATES PATENT OFFICE.

WALDO L. KRAEMER, OF BROOKLYN, NEW YORK, ASSIGNOR TO KEARFOTT ENGINEERING COMPANY, INC., A CORPORATION OF NEW YORK.

WINDOW OPENER.

Application filed December 23, 1926. Serial No. 156,641.

My invention relates to window control gear, and particularly to window opening and closing devices for use on shipboard.

The windows of many types of habitable structures are frequently opened and closed, and in certain types of structures it is essential that very substantial, positive, actuating means be provided for the opening and closing. This requirement is particularly important in the case of ships and other similar transportation vehicles in which it is required that windows be provided, and that positive means for opening and closing the windows be installed, in order that under conditions of bad weather the windows may be firmly closed to exclude water, wind, and other objectionable manifestations of the elements.

The service required of windows under such conditions is particularly severe since they are subject to frequent opening and closing, and the guiding ways are frequently wet or clogged with ice or other substances, and may be racked and twisted by the movement of the main structure in which they are positioned. In consequence, any window controlling structure, in order to be satisfactory, must be very rugged, very powerful, and not easily put out of operation by twisting or the presence of obstructions.

My invention consists of a window and operating means, and provides a clear pane of glass having no window-frame, but adapted to cooperate with guiding ways positioned in the window casing. The pane of glass is attached to a clamp at its lower edge, and a traversing screw with actuating gears, a handle and a traversing nut are provided. The nut has engaging members which cooperate with the clamp attached to the glass pane to carry it up and down under the control of the traversing screw when movement is imparted thereto by the gears and attached handle, by the user. The structure provides suitable play between the various elements thereof at the points where warping or twisting of the window casing might tend to cause a binding and thereby difficulty of operations. My device is desirably formed from non-corrosive materials such as bronze, and it is very well adapted to service in the presence of salt spray, and when so used shows no tendency

to stick or fail because of corrosion of its various parts.

By the device of my invention, I provide means to meet all of the previously mentioned requirements, and to obtain many new and useful results which will be apparent from the following description when read in connection with the accompanying drawings, wherein:

Fig. 1 is a view in vertical front elevation with the covering panels removed, of a preferred embodiment of my invention;

Fig. 2 is a view in horizontal section of the same embodiment;

Fig. 3 is a view in transverse section of the same embodiment, and

Fig. 4 is a view in vertical elevation, partly in section of the traversing nut member of the same embodiment.

Referring to the drawings, I provide a window casing 1 to which are secured guide-ways 2 which may desirably be padded with felt 3. A pane of glass 4 is adapted to slide in the ways 2, without the necessity of a sub-frame as is now required.

The glass pane 4 is supported and positioned by a clamp member 5 attached to the lower edge thereof. The clamp 5 may desirably consist of an angle member 6 as indicated in Fig. 3, having a bearing ledge 7 at the lower edge. A clamping plate 8 is provided and held in place by screws 9. A packing 11 which may be of rubber sheet or other suitable material is desirably provided between the metal parts of the clamp and the glass.

A traversing screw 12 is provided, and mounted in a special bearing 14 at the bottom. The bearing is desirably attached to the bottom member of the window casing 1. A breast-rail member 15 is provided having a journal bearing member 16, substantially at the midpoint thereof and adapted to support the upper end of the traversing screw 12. Actuating gears, which may be a pair of spiral gears 17 and 18 are provided, the smaller gear 17 being attached to the upper end of the traversing screw 12. Bearing washers 19 are provided between the gear 17 and the journal bearing 16. Another bearing washer 21 is positioned surrounding the screw 12, and a nut 22 is threaded over the

projecting end of the screw 12, and caused to bear gently against the washer 21 to secure a smooth easy bearing fit, and is held by a suitable cotter-pin 23. The screw 12 is thus firmly held in place between the bearing 16, in the breast-rail 15, and the step bearing 14. The thrust upon said screw due to the load imposed upon it in the opening or closing of the window is in both cases transmitted to and 10 carried by the journal bearing 16 which is rigid with the breast rail 15. The gear 18 is mounted upon a shaft 24 which is provided with a square end 25 which is adapted to cooperate with a crank handle 26. The shaft 15 24 is passed through a suitable bearing in the breast-rail 15, as indicated. A bracket 27 is provided, attached to the breast-rail and provided with a journal bearing 29 adapted to cooperate with the shaft 24. The bearings 20 in the breast-rail and bracket hold the gear 18 and the shaft 24 firmly in place and maintain accurate mesh between the gears 17 and 18. The breast-rail 15 is preferably formed of a casting having a special channel section and 25 is thus sufficiently stout to maintain accurate mesh between the gears 17 and 18 without regard to twisting forces which may be applied to it. Likewise the gear 17 is closely adjacent to the bearing 16 for the traversing screw 30 12, which bearing is a part of the breast-rail and accordingly even an extreme amount of twist or displacement of the screws will not serve to disturb the meshing of the gears. By this means very smooth, firm, accurate operation of the screw and gears is obtained.

The spiral gears as described for the actuation of the traversing screw 12 are particularly advantageous in the device of my invention, since they permit the utilization of large, 40 rugged, durable gears in the very restricted space available. The utilization of any other type of gear involves either a widening of the space between the window and the casing in which the opening device works or the use of 45 such small gears that a very serious loss in strength and durability occurs.

A nut 31, as shown in detail in Fig. 4, is provided to cooperate with the screw 12. As shown, the nut is desirably formed of a casting, of a metal such as bronze. The threads therein may be formed by tapping from the solid metal, but I find it desirable to use a high-pitch square-thread on the screw 12, and it is preferable that the nut 31 be threaded in 50 another manner, since an internal thread of the type described is difficult to cut from the solid metal. I prefer to form the thread within the nut 31 by casting therein a liner 32, of a bearing metal such as babbitt, which 55 may desirably be cast about a mandrel of substantially the size and shape of the traversing screw 12. The babbitt may be anchored within the nut 31 in any convenient customary way, as by projections or pockets. 60 The thread may desirably be finished after

casting the babbitt, and removing the mandrel, by passing a suitable tap therethrough adapted to take a light finishing cut off of the inner surfaces. The nut 31 is provided with a collar 33 integral therewith, at the lower 70 edge thereof, and with an integral hook member 34.

A cooperating link member 35 is provided and attached to the clamp 5 and the glass pane 4 by screws 36. The link member 35 is provided with forwardly projecting arms 37, which are adapted to cooperate with projections 38 upon the collar member 33 of the nut 31. The weight of the glass pane is thus carried through the clamp 5, the link member 80 35, the arms 37, the collar 33, and the nut 31, upon the threads of the screw 12 and is accordingly raised and lowered by upward or downward motion of the nut from rotation of the screw by the gears and handle. 85

The projections 38 upon the collar 33 of the nut 31 are particularly advantageous in their cooperation with the arms 37 upon the link member 35, since they permit a very free positioning of the nut with respect to the glass 90 4 and the various clamping members, in the upward and downward movement. This is particularly important because of the fact that it avoids any binding of the nut upon the threads of the screw 12 which might otherwise occur if the nut were rigidly fastened to the link member and the glass, likewise it avoids the production of sidewise stresses which might otherwise tend to break the glass. The structure, as shown, carries the 100 weight of the glass upon the nut, with only a downward component of pressure upon the nut and no sidewise, or twisting, components. This is particularly advantageous since it provides for very smooth and easy operation 105 of the device, and is of substantial advantage under difficult operating conditions as may occur when there is a severe racking of the structure.

The hook member 34 of the nut 31 is adapted to enter an opening in the link member 35 above the lower cross portion to which the arms 37 are attached. Under normal conditions when the window operates freely, the hook 34 does not function. When, however, 110 the window-pane is stuck, as may occur when spray freezes upon the outer surface, the weight of the window-pane may not be sufficient to free it from the grip of the ice, and accordingly the window may not open upon movement of the screw and nut downward. 115 A small additional movement then brings the hook 34 into engagement with the link member 35 and a strong downward pull may be exerted thereon by continued rotation of the screw, which may be sufficient to free the window and permit its downward movement. In the event that the window-pane is too firmly attached, however, and vigorous efforts are 120 made to free it by actuation of the operating 125 130

means, no damage will be done the window-pane since the downward pull produced by the hook 34 has no twisting component but only a straight downward pull with no tendency to break off the lower edge of the glass as might otherwise occur if the arms 37 were firmly attached to the nut 31. Instead the worst that can happen is the application of sufficient pull to draw the clamp 5 off of the lower edge of the window-pane, upon which it is easily replaced by loosening the screws 9, adjusting in proper place and retightening.

It is to be noted that in the above described operation which occurs when a downward pull is necessary, to open the window, that the force components are reversed as compared to those produced under normal operation. When the downward pull is exerted, upon the glass, a downward force only is applied to the clamping member and no sidewise forces are applied which might tend to break the glass. All of the sidewise and twisting components produced are concentrated in the nut. This disposition of forces does not avoid the tendency which may occur for the nut to work less easily upon the screw. This feature is however of advantage since it tends to prevent the application of undue forces to open the window and reduces the chance of sufficient force being applied to pull the clamp away from the bottom edge of the glass.

The device of my invention is particularly adapted to the actuation of heavy window-panes without the use of a subframe, since the mechanism is conveniently attached directly to the pane of glass. This construction is particularly advantageous because of the wide view obtainable and the lack of obstructing auxiliary frames.

By the device of my invention I have thus produced a simple, easily operated, rugged, durable and convenient window controlling device, which is particularly adapted to ship

and other service and which is relatively inexpensive to build because of the small number 45 and simplicity of the parts.

While I have shown but a single embodiment of the device of my invention in the accompanying description, it is capable of various modifications therefrom without departing from the spirit thereof, and it is desired, therefore, that only such limitations shall be imposed thereon as are required by the prior art or indicated by the appended 50 55 claims.

I claim as my invention:

1. In a window opener, holding means adapted to receive the lower edge of the window pane, a travelling nut, means for loosely connecting said nut with said holding means for operating the same in both upward and downward directions, a screw shaft for traversing said nut, a bearing for supporting the upper end of said shaft and sustaining the thrust thereof in both directions, a support 60 65 rigid with said bearing, and means extending through said support and supported thereby for operating said shaft.

2. In a window opener, holding means adapted to receive the lower edge of the window pane, a travelling nut, means for loosely connecting said nut with said holding means for operating the same in both upward and downward directions, a screw shaft for traversing said nut, a bearing for supporting the upper end of said shaft and sustaining the thrust thereof in both directions, a spiral gear on said shaft adjacent said bearing, a support 70 75 rigid with said bearing, and means extending through said support and supported thereby for operating said shaft, said means comprising a spiral drive gear.

In witness whereof, I hereunto subscribe my signature.

WALDO L. KRAEMER.
